CIRCUIT BREAKER

William Lawrence Butler, Schenectady, N. Y., assignor to General Electric Company, a corporation of New York

Application June 19, 1942, Serial No. 447,625

12 Claims. (Cl. 200—116)

My invention relates to circuit breakers and particularly to a new and improved form of the manually operated overcurrent trip circuit breaker of the general class described in my Patent 2,230,713, issued February 4, 1941 on an application filed October 25, 1939. More specifically, the present invention is an improvement upon the circuit breaker illustrated in my co-pending Patent No. 2,300,202, issued October 27, 1942.

The principal object of my invention is to provide a simple and reliable manually operable current responsively tripped circuit breaker which is trip-free in its automatic operation and which may be easily manufactured in large quantities and at low cost.

My invention is especially useful in manually operated current responsively tripped circuit breaker which is trip-free in its automatic operation and which may be easily manufactured in large quantities and at low cost.

My invention is especially useful in manually operated current responsively tripped circuit breakers used for the connection of small motors directly across a supply source without starting resistance. These devices are of small physical dimensions and at the present time are used with motors up to two horsepower at 440 volts.

To the attainment of the foregoing and other objects, my invention is preferably embodied in the detailed construction to be hereinafter more fully described and claimed and is illustrated in the accompanying drawings in which Fig. 1 is a front view of a three-phase automatic motor starting switch embodying my invention; Fig. 2 is a sectional view taken along the line 2—2 of Fig. 1 looking in the direction of the arrows and showing the operating mechanism in its "on" position; Fig. 3 is a side elevation of the operating mechanism with one of the lateral supporting plates removed to show the mechanism in its manual "off" position; Fig. 4 is a view similar to Fig. 3 showing the operating mechanism in its automatic "trip" position; Fig. 5 is a view similar to Figs. 3 and 4 showing the operating mechanism in its "reset" position; Fig. 6 is an exploded perspective view having various parts broken away to show the automatic overcurrent trip mechanism and the operating mechanism, the operating mechanism being shown in its "on" position; and Fig. 7 is a sectional view of the current responsive tripping element.

Referring now to the drawings, my invention in the form shown comprises a circuit breaker mechanism mounted upon a base 10 made of

electrically insulating material, such as a suitable molded compound, the base 10 being seated within an external casing 11 having a cover 12. The base 10 has an irregular shape determined by convenience in supporting the various parts of the device. The switch-actuating mechanism is borne upon a pair of supporting plates 13 and 14 which are secured rigidly to the base 10, as by bolts 15 and 16, respectively, and extend therefrom in parallel spaced relation, the operating mechanism being mounted between the plates on suitable pivot pins extending therebetween. A manually operable operating linkage comprises a pair of push buttons 17 and 18 connected to opposite ends of a rocker arm 19 which is pivotally mounted upon a pin 20 journaled in the plates 13 and 14. The push buttons 17 and 18 are attached to slotted bars 17a and 18a respectively, which engage notched ends of the arm 19 and are held in place on the rocker arm 19 by a transversely bent spring strip 19a. The spring strip 19a overlies the arm 19 and is notched at its ends to engage the slotted bars 17a and 18a. This construction permits the necessary angular motion between the bars 17a and 18a and the arm 19 but prevents rattling. One side of the rocker arm 19 is connected by a link 21 to a switch-actuating lever 22 which is pivotally mounted upon a pin 23 journaled in the lateral supporting plates 13 and 14. The actuating lever 22 is operated in the manner of a bell crank due to the fact that the link 21 is pivotally attached by a pin 24 to a short arm 25 extending from the side of the lever 22 opposite its pivot point 23.

As best shown at Fig. 6, a movable switch member 26 is mounted as a floating lever and is of irregular shape for the accomplishment of a plurality of functions which will appear hereinafter. Fundamentally, the lever 26 comprises a pair of substantially parallel end portions 27 and 28 and an offset intermediate portion 29 having a camming surface 30 and notch 31 formed on the lower edge thereof for cooperation with a pin or roller 32 fixed to the actuating lever 22. In order that the floating lever 26 and the actuating lever 22 shall be interlockingly engaged at all times and for certain other purposes to be hereinafter more fully described, the actuating lever 22 is also provided at its upper end with a second pin or roller 33 engageable with a shoulder 34 and second camming surface 34a on the upper edge of the floating lever 26. The end portion 27 of the floating lever 26 is provided with a downturned latching portion 35

to which is rigidly attached a transverse latching dog and pivot pin 36 which is slidably and pivotally supported in a pair of curved slots 37 in the lateral supporting plates 13 and 14.

The member 36 is normally held in fixed position and serves as a pivotal support for the end 27 of the floating lever 26. The floating lever is normally biased to a switch-opening position against a fixed stop pin 26a by a compression spring 26b and is engaged intermediate its ends by the actuating lever 22 to move it to a switch-closing position. The spring 26b is disposed between the free end 28 of the floating lever 26 and one end of the rocker arm 19, thereby simultaneously to bias the floating lever to a switch-opening position and the rocker arm 19 and actuating lever 22 to an "off" position. To retain the free end of the lever 26 in mid-position between the supporting plates 13 and 14, a centering pin 26c is attached to the free end 28 of the lever 26.

The free end 28 of the floating lever 26 is fitted as a tongue into a slot formed in the upper end of a T-shaped slidable link 38. The link 38 is preferably formed of rigid insulating material and comprises the slotted portion loosely attached to the floating lever 26 and a transverse arm slotted at three points 39, 40, and 41 for the reception of resilient contact-carrying members 42, 43, and 44 respectively. This construction is best shown at Fig. 6. Each contact-carrying member 42, 43, and 44 is formed of electrically conducting spring material, such as an alloy of copper, and carries at its one end a movable contact member 45 for cooperation each with a fixed contact 46. The opposite end of each contact-carrying member 42, 43, and 44 is rigidly attached to the base 10, as by a bolt 47, best shown at Fig. 2.

As shown at Figs. 1 and 2, each fixed contact 46 is mounted upon a conducting strip 46a one end of which projects into a recess 48 in the base 10 and the other end of which is mechanically and electrically connected to a terminal 49. The opposite terminals 50 of the breaker are electrically connected to the fixed ends of the resilient contact-carrying members by means of a jumper 51 of Fig. 2 for the center phase and through current responsive tripping mechanisms generally designated as 55 for each outside phase.

It will be understood that each of the two outside phases of the three-phase switch are provided with a current responsive tripping mechanism 55. Each of these mechanisms includes an electric heater 56 connected in series circuit relation between the contact strips 42 and 44 and the breaker terminals 50, as will be more particularly described hereinafter. Since the current responsive tripping mechanisms in both outside phases are identical, only one such mechanism will be described in detail. A single latching mechanism designated generally as 58 is provided intermediate the lateral supporting plates 13 and 14 in connection with the single centrally mounted floating lever operating mechanism. The latching mechanism 58 is adapted to be independently operated by either current responsive tripping mechanism 55, as will appear more clearly hereinafter.

Referring now particularly to Figs. 6 and 7, the current responsive tripping mechanism is supported upon a generally L-shaped metallic base 60 which is preferably channel-shaped in cross section. One leg of the channel-shaped support 60 lies along the movable contact strip 42 and the other leg of the member 60 extends

substantially at right angles to the contact strip 42 and is provided at its ends with a flange 60a. Bolted to the flange 60a and extending substantially in alignment with the upstanding leg of the support 60, I also provide a current-conducting and supporting plate 61. The supporting structure is completed by an L-shaped angle bracket 62 welded to the supporting plate 61 and extending laterally therefrom. The bracket 62 is provided with an extension 62a which extends in parallel spaced relation with the supports 60 and 61 and beyond their point of intersection. The extension 62a is welded to the channel-shaped support 60 thereby to strengthen the joint between the support 60 and the support 61.

For the purpose of connecting the electric heater 56 in series circuit relation between the contact strip 42 and the terminal 50, and also for the purpose of strengthening and holding in place the supporting structure described in the preceding paragraph, an L-shaped current-conducting strap 63 may be connected between the contact member 42 and the flange 60a. As shown, one leg of the conductive strap 63 lies along the contact strip 42 between the strip 42 and the channel-shaped support 60. The members 42, 60, and 63 are all welded together.

By means of a small offset spring strip 64 attached to the channel-shaped support 60, a U-shaped current responsive actuating element is adjustably supported in parallel spaced relation with respect to the upstanding leg of the supporting structure 60, 61. The actuating element comprises an L-shaped mounting strip 65 and a thermo-responsive bimetallic strip 65a. Thus the U-shaped thermo-responsive actuating element 65, 65a is pivotally mounted at its bight, and the normal position of the bimetallic strip 65a is determined by the position of the mounting strip 65 with respect to the fixed base structure 60, 61. To determine the position of the mounting strip 65, I provide a pair of adjustable bolts 66 and 67 for varying the spacing between the upper or free end of the mounting strip 65 and the adjacent portion of the supporting plate 61. The bolt 66 passes through the current-conducting supporting plate 61 and the connected supporting bracket 62 into threaded engagement with the upper end of the mounting strip 65. The bolt 67 threadingly engages the supports 61 and 62 and extends into only abutting engagement with the mounting strip 65, thereby to determine a minimum spacing between the mounting strip and the support 61.

As shown in Figs. 6 and 7, the electric heater 56 has one end connected to the current-conducting support 61 and extends down between the legs of the U-shaped actuating element 65, 65a, so that it is in intimate heat-conducting relation with respect to the bimetallic strip 65a. It will be understood that the other end of the electric heater 56 is connected directly to the breaker terminal 50, so that current is conducted from the contact member 42 to the terminal 50 through a path comprising the conducting strap 63, the current-conducting support 61, and the electric heater 56.

The bifurcated bracket 62 serves pivotally to support an overcenter trip lever 70, one arm of which is engaged by the bimetallic strip 65a and the opposite arm of which is arranged to engage the tripping element of the latch mechanism 58. As indicated at Fig. 6, the bifurcated arm of the bracket 61 has attached thereto, as by welding on the side adjacent the breaker operating mech-

anism, a thin, flat, U-shaped plate 71, the bight of which extends across the base of the bifurcated leg of the bracket 61 and the arms of which extend in parallel relation with the arms of the bracket. The arms of the plate 71 are wider than those of the bracket 61 so that they overhang the inner edges of the bracket arms to form adjacent each arm a knife-edge bearing adapted to support the trip lever 70 by seating in a V-shaped notch 72 between the oppositely extending arms of the trip lever. The trip lever 70 is endowed with a snap action by means of an overcenter spring 73 connected between the bight of the bearing plate 71 and a transverse strap 74 on the lever 70.

Since each outside phase of the breaker is provided with a current responsive tripping mechanism 55 of the type described above, there is a trip lever 70 positioned on each side of the breaker operating mechanism, each lever having a latch arm extending through an opening 75 in the adjacent lateral supporting plate 13 or 14. This is best illustrated at Figs. 1 and 6. As clearly illustrated by the broken line projection in Fig. 6, the inwardly extending arms of the trip levers 70 are positioned to engage and independently to operate a pivoted latch member or latch lever 90 forming part of the latching mechanism 55. The latch lever 90 is welded to a pivot pin 91 which is journaled in the side supporting plates 13 and 14. The latch lever 90 is arranged to hold in latching position a second pivoted latch member or trip lever 92 which is likewise supported in the plates 13 and 14 by a pivot pin 93 to which it is attached as by welding. The trip lever 92 is provided with a detent 94 for latching engagement with the dog 36 of the floating lever 26. This construction is best shown at Fig. 6.

When the latch lever 90 and trip lever 92 are in latching position, they lie in substantially parallel spaced relation, and to retain the trip lever 92 in latching position it is provided with an arm 95 formed at its ends into a tongue 96 having at least two contiguous portions of different widths. As shown at Fig. 6, the tongue 96 is formed by providing a reduced section between the body of the tongue and its outer extremity, the reduced section having two contiguous portions of different widths. The outer extremity of the tongue serves as a locking bar for preventing complete disengagement of the tongue with a cooperating slot in the latch lever 90, and serves also as a camming member in reset operation as will be more fully described hereinafter. The slot in the latch lever 90 is indicated by the reference numeral 97 and, for cooperation with the two contiguous reduced portions of the tongue 96, the slot 97 is formed to provide two contiguous portions of corresponding widths, the narrowest portion of the slot being adapted to receive the narrowest section of the tongue 96 and the wider portion of the slot being adapted to receive the wider reduced section of the tongue. The latching shoulder between the two contiguous portions of the slot 97 is located adjacent a slightly offset shoulder portion of the latch lever 90 arranged to be engaged by the extremity of the tongue 96 for a purpose which will appear hereinafter. A tension spring 100 is connected between the latch lever 90 and the trip lever 92 on opposite sides of their pivot points, so that both levers are biased for clockwise rotation, as viewed in the drawings, thereby to bias the latch lever 90 toward and into latching en-

gagement with the trip lever 92 and simultaneously to bias the trip lever 92 to a latch-releasing position with respect to the floating lever 26. I have also shown a small cantilever spring 101 carried by the lever 92 and passing loosely through the slot 91. This spring engages the base of the slot 91 in resetting operation only for a purpose which will be described hereinafter.

Referring now particularly to Fig. 6, the operation of my new and improved circuit breaker will be clear. At Fig. 6 the mechanism is shown in the manual closed position. In this position the pivot pin and latching dog 36 is held at the base of the slots 31 by engagement of the detent 34 with the latching dog, while the free end 28 of the floating lever and the slidible link 38 are held in raised position by engagement of the pin 32 on the actuating lever 22 with the notch 31 at the lower end of the camming surface 30 of the floating lever 26. In arriving at this position the floating lever 26 was raised slightly beyond its manual closed position before the pin 31 fell into slot 32. Such overtravel of the operating mechanism is permitted by the resilience of the contact members 42, 43, and 44. In the position shown in Fig. 6, the pin 31 is held in frictional latching engagement with the slot 32 by means of the compression spring 26b as well as by the spring force of the contact-carrying members 42, 43, and 44 which are slightly deformed in the closed position of the switch. In this position the compression spring 26b also biases the rocker arm 19 and the actuating lever 22 to the "off" position, but movement of the actuating lever 22 to the "off" position is prevented by friction catch comprising the pin 32 and the notch 31. The compression spring 26b itself aids in making this friction catch effective in so far as it aids in forcing the pin 32 into the slot 31.

The contacts may be opened manually by depressing the push button 18 to rotate the rocker arm 19 in a clockwise direction about its pivot point 20 to the position shown at Fig. 3. By this movement the link 21 is constrained to exert an upward force upon the short crank arm 25 of the actuating lever 22, thereby to force the pin 32 out of the slot 31 and to rotate the actuating lever 22 in a clockwise direction about its pivot point 23, as viewed in the drawings, until the pin 33 at the upper end of the lever 22 engages the upper camming surface 34a at the end 27 of the floating lever 26. During this retractive movement of the actuating lever 22 the free end 28 of the floating lever 26 is moved by the spring 26b toward a circuit-opening position as the camming surface 30 rides along the pin 32. The mechanism is shown in its manual open position at Fig. 3.

Manual closing operation of the switch is simply the opposite of the opening operation described immediately above. For manual closing the push button 17 is depressed to cause the actuating lever 22 to pivot in a counterclockwise direction, thereby to raise the floating lever 26 to its circuit-closing position by camming action of the pin 32 along the camming surface 30.

Assuming now that the mechanism is in the closed position shown at Figs. 2 and 6, an automatic tripping operation upon the occurrence of an excessive current may be traced. The tripped position of the mechanism is shown at Fig. 4. Upon the occurrence of a predetermined excessive current the heat generated in the electric heater 56 first deforms the bimetallic strip

65a and causes its free end to move the trip lever 70 slowly in a counterclockwise direction, as viewed in Fig. 6. As soon as the spring 73 is carried overcenter, the trip lever 70 continues its movement with a snap action under the influence of the overcenter spring 73 and brings that arm of the lever 70 which extends through the lateral supporting plate 13 into engagement with the free end of the latch lever 90 with a hammer blow, thereby to move the lever 90 in a counterclockwise direction as viewed at Fig. 6. Counterclockwise movement of the latch lever 90 brings the narrow portion of the slot 97 into juxtaposition with respect to the narrowest reduced section of the tongue 96 and at the same time applies a certain amount of additional tension to the latch spring 100. As soon as the tongue 96 is released by movement of the slotted latch lever 90, the trip lever 92 is free to rotate about its pivot pin 93 in a clockwise direction under the influence of the latch spring 100. Clockwise rotation of the trip lever 92 removes the detent 94 from the path of the latching dog 36 and frees the normally fixed end 27 of the floating lever 26. It will be noted that the force exerted by the compression spring 26b tending to rotate the floating lever 26 about the pin 32 also tends to raise the end 27 of the floating lever and thus pulls upward on the detent 94 and assists in rotating the trip lever 92 in a clockwise direction.

Upon disengagement of the detent 94 from the latching dog 36, the floating lever 26 rotates about the pin 32 on the actuating lever 22 under the influence of the main spring 26b. Such rotation causes the free end 28 of the floating lever to move downwardly into engagement with the fixed stop pin 26a carrying with it the slidable link 38, thereby to open the breaker contacts. As may now be clearly observed from Fig. 4, when the floating lever is in engagement with the fixed stop pin 26a, the biasing force of the movable switch contact members 42, 43, and 44 which formerly retained the pin 32 in the slot 31 is no longer present. The biasing force of the compression spring 26b is also considerably diminished due to its extension. Furthermore, the free end 28 of the floating lever 26 has taken up such a position that the notch 32 is, in a sense, opened up, so that it no longer offers any considerable frictional resistance to displacement of the pin 31 from the notch and along the camming surface 30. Therefore the upward force exerted by the compression spring 26b upon the rocker arm 19 raises the link 21 and turns the actuating lever 22 in a clockwise direction until the pin 33 comes into engagement with the shoulder 34 on the upper edge of the floating lever 26. By this movement the pin 32 is released from the notch 31 and the pin 33 serves as an upper stop for the normally fixed end 27 of the floating lever 26. From Fig. 4 it may now be observed that in the tripped position the actuating lever 22 and the rocker arm 19 take up positions intermediate their manual "on" and "off" positions. However, the rocker arm 19 is only loosely held in the tripped position so that no harm would come to an operator in attempting to retain the operating linkage in its manual "on" position while the overcurrent trip mechanism functions. Furthermore, even if the push button 17 is held depressed so that the operating linkage is held in the "on" position and the pin 32 can not be displaced from the notch 31, the breaker contacts will be opened. These features constitute "trip-free" operation.

To reset the breaker mechanism after an automatic tripping operation such as that described above, the rocker arm 19 must be moved beyond its manual open position by depression of the push button 18. The reset position of the mechanism is shown at Fig. 5, and by comparison of Figs. 4 and 5 it may be seen that the clockwise rotation of the rocker arm 19 in resetting operation forcibly raises the link 21 to rotate the actuating lever 22 in a clockwise direction. Such clockwise rotation of the actuating lever 22 effects a clockwise rotation of the floating lever 26 about the stop pin 26a by reason of the pressure of the pin 33 against the shoulder 34. As the latching dog and pin 36 moves downwardly in the slots 37 and the normally fixed end 27 of the floating lever 26 approaches its normal latched position, the pin 33 slides off of the slightly inclined shoulder 34 and rides along the top camming surface 34a of the floating lever while it continues to force the end 27 of the floating lever downwardly. During this movement the projecting end 35 of the floating lever engages the arm 95 of the trip lever 92 and rotates the trip lever about its pivot pin 93 in a counterclockwise direction, as viewed at Fig. 5, until the tongue 96 of the trip lever 92 comes adjacent the wider portion of the slot 97 in the latch lever 90. When the tongue reaches this position, which is the normal latched position of the latch members, the spring 100 rotates the latch lever 90 clockwise so that the wider reduced portion of the tongue 96 falls into the wider portion of the slot 97 and the detent 94 reengages the dog 36. To fully reset the mechanism, however, the button 18 must be still further depressed to rotate the trip lever 92 counterclockwise beyond its normal latched position to the reset position of Fig. 5. In moving to the position of Fig. 5, the wide end portion of the tongue 96 engages an offset portion of the latch lever 90 formed to provide an inclined shoulder 113. The shoulder 113 now serves as a camming surface positively to rotate the latch lever 90 in a clockwise direction beyond its normal latched position. As shown at Fig. 5, this overtravel of the member 90 causes it to engage the tripping arm of the trip-free lever 70, thereby to move the trip lever 70 back overcenter and reset the current responsive tripping mechanism 55. The overtravel of the lever 92 causes the spring 101 to engage the base of the slot 97 thereby to apply an additional return force to the lever 92. It will be understood of course that such resetting of the mechanism 55 may be effected only if the bimetallic strip 55 has cooled and returned to its normal position. Upon release of the push button 18 the latch spring 100, aided by the spring 101, rotates both the members 90 and 92 in a clockwise direction through a small angle to their normal latched positions until the tongue 96 again engages the shoulder adjacent the contiguous portions of different width of the slot 97 as shown at Fig. 3. This last small movement of the trip lever 92 raises the normally fixed end 27 of the floating lever 26 so that the pin 36 is slightly removed from the lower end of the slots 37. The compression spring 26b then brings the latching dog and pin 36 into engagement with the detent 94. In moving back to the position of Fig. 3, the floating lever 26 engages the pin 33 on the actuating lever 22 and moves the actuating lever and the rocker arm 19 back to their manual open position of Fig. 3. All the parts are

now fully reset as shown at Fig. 3 and prepared for manual operation to close the breaker to the positions shown at Figs. 2 and 6.

While I have described but a single preferred embodiment of my invention, many modifications will occur to those skilled in the art. For example, while I have illustrated my invention as applied to a three-phase motor starting switch provided with two overcurrent trips for three-phase protection, it will be understood that my operating and matching mechanism may be used to operate any desired number of switch contacts and may be combined with any desired number of my independent overcurrent trip mechanisms. I therefore wish to have it understood that I intend in the appended claims to cover all such modifications as fall within the true spirit and scope of my invention.

What I claim as new and desire to secure by Letters Patent of the United States, is:

1. A push button operated circuit breaker comprising cooperating switch contacts, a floating lever having a first end connected to move one of said contacts, means for slidably and pivotally supporting said lever at at least one end, a manually operable operating linkage comprising a pivotally mounted actuating lever slidably and interlockingly engaging said floating lever intermediate its ends and a push button actuated rocker arm pivotally mounted intermediate its ends at a fixed point and linked with said actuating lever to control the movement thereof, releasable latch means for normally retaining the other end of said floating lever in a position fixed with respect to said fixed point, said floating lever providing friction catch means arranged to engage said actuating lever for retaining said floating lever in a contact-closing position, a spring connected between said floating lever and a movable position of said operating linkage to bias said floating lever to a contact-opening position and said linkage to an off position while biasing said friction catch means into engagement with said actuating lever, and means responsive to the current traversing said contacts for releasing said latch means.

2. A push-button operated circuit breaker comprising cooperating switch contacts, a floating lever having one end connected to move one of said contacts and formed to provide a camming portion intermediate the ends thereof, means for slidably and pivotally supporting the other end of said floating lever, an actuating lever pivoted at a fixed point and slidably and interlockingly engaging said camming portion, said camming portion including a friction catch for retaining said actuating lever in a contact-closing position, a push button actuated rocker arm pivoted intermediate its ends at a second fixed point and having one end mechanically connected to said actuating lever to control movement of said actuating lever, releasable latch means for normally retaining said other end of said floating lever in a fixed position with respect to said fixed points, spring means operatively connected between said floating lever and said rocker arm for biasing said actuating lever and said rocker arm to an off position and biasing said floating lever to a contact-opening position and into engagement with said friction catch, and means responsive to the current traversing said contacts for releasing said releasable latch means.

3. A push button operated circuit breaker com-

prising cooperating switch contacts, a floating lever for moving one of said contacts, said floating lever having a normally fixed end and a free end connected by an intermediate portion providing a camming surface, a pin and slot connection for slidably and pivotally supporting said normally fixed end of said floating lever, releasable latch means for normally restraining sliding movement of said normally fixed end, a manually operable operating linkage comprising a pivotally mounted actuating lever and a push button actuated rocker arm, having one end connected to said actuating lever, said actuating lever providing means intermediate its ends for interlockingly engaging said intermediate portion of said floating lever, spring means connected between said manually operable operating linkage and said floating lever for biasing said linkage to an off position and said floating lever to a contact-opening position, and means associated with said floating lever for retaining said actuating lever in an on position against the bias of said spring means thereby to retain said floating lever in a contact closing position.

4. A push button operated circuit breaker comprising a fixed contact, a resiliently mounted movable contact, a pair of slotted lateral supporting plates, a floating lever having a free end connected to move said movable contact and a normally fixed end spaced from said free end and joined thereto by an offset intermediate portion providing a camming surface, a pin attached to said normally fixed end of said floating lever and arranged for slidable and pivotal engagement with said lateral supporting plates, stop means for limiting movement of said free end of said floating lever, an actuating lever having one end pivotally mounted at a fixed point in said supporting plates, said actuating lever having a laterally extending arm and providing means intermediate its ends for interlocking engagement with said intermediate portion of said floating lever, a manually operable push button actuated rocker arm pivotally mounted at its center in said supporting plates, a linkage connecting one end of said rocker arm to said laterally extending arm of said actuating lever, current responsive latch means for releasably restraining said normally fixed end of said floating lever against sliding movement, a main spring connected between said floating lever and said rocker arm to bias said actuating lever and said rocker arm to an off position and to bias said floating lever to a contact-opening position, and a friction catch for releasably retaining said actuating lever in an on position against the bias of said main spring, both said main spring and said resiliently mounted contacts supplying pressure to said friction catch to retain said floating lever in a contact-closing position against the bias of said main spring.

5. A push button operated circuit breaker comprising a support, a fixed contact mounted upon said support, a floating lever having one end slidably and pivotally mounted upon said support, current responsive latch means for normally restraining sliding movement of said one end of said floating lever, stop means for limiting movement of the other end of said floating lever, a movable contact operatively associated with said other end of said floating lever, an actuating lever pivotally mounted upon said support and engaging said floating lever intermediate its ends to rotate said floating lever about said one end

thereby manually to engage said contacts, a push button actuated rocker arm pivotally mounted at its center upon said support and having one end mechanically connected to said actuating lever for manual control of said actuating lever, and biasing means connected between said one end of said floating lever and said one end of said rocker arm normally to bias said floating lever to a switch-opening position and to bias said actuating lever and said rocker arm to an off position, said biasing means being operable upon release of said latch means to rotate said floating lever about its point of engagement with said actuating lever thereby to disengage said contacts regardless of the position of said rocker arm.

6. A circuit breaker comprising a slotted support, a fixed contact mounted upon said support, a floating lever having at one end a pin arranged slidably and pivotally to engage said slotted support, stop means for limiting movement of the other end of said floating lever, current responsive latch means for normally restraining sliding movement of said one end of said floating lever, a resiliently mounted movable contact operatively connected to the other end of said floating lever, said floating lever intermediate the ends thereof being formed by upper and lower camming surfaces, an actuating lever pivotally mounted at a fixed point upon said support, means associated with said actuating lever for engaging said lower camming surface to rotate said floating lever about said one end for manually engaging said contacts, a push button actuated rocker arm pivotally mounted at its center upon said support and having one end mechanically connected to said actuating lever to control movement of said actuating lever, a biasing spring connected between one end of said floating lever and one end of said rocker arm to bias said floating lever to a contact-disengaging position and said rocker arm to an off position, said spring being operable upon release of said latch to rotate said floating lever about its point of engagement with said actuating lever to disengage said contacts regardless of the position of said rocker arm, and means associated with said actuating lever to engage said upper camming surface for rotating said floating lever about said stop means to reset said latch means.

7. An automatic circuit breaker comprising a support, cooperating switch contacts, a movable switch member for moving one of said contacts, a trip lever pivotally mounted upon said support and being provided at one side of its pivot point with a detent normally engaging said switch member, a projecting tongue attached to said trip lever and formed to provide contiguous portions of different widths, a latch lever pivotally mounted upon said support and having a portion on one side of its pivot point offset to provide a camming shoulder, said latch lever provided with a slot having contiguous portions of different widths to form a latching shoulder therebetween, said trip lever and said latch lever being interlockingly engaged for cooperation of corresponding portions of said tongue and said slot, said tongue being provided with an end portion wider than the widest portion of said slot for retaining said levers in interlocking engagement and for cooperation with said camming shoulder, a tension spring connected between said one end of said latch lever and the other end of said trip lever thereby to bias said latch lever to secure said trip lever and to bias said trip lever to release said detent, an overcenter lever for actuating

said latch lever in opposition to said spring thereby to release said trip lever, thermal means responsive to the current passing through said contacts for actuating said overcenter lever, and means associated with said switch member to move said end portion of said tongue into engagement with said camming shoulder thereby to reset said trip lever, said latch lever, and said overcenter lever.

10. An automatic circuit breaker comprising a support, cooperating switch contacts, a movable switch member for moving one of said contacts, a trip lever pivotally mounted upon said support and having a detent arranged to engage said switch member, a projecting arm connected to said trip lever and extending at substantially right angles thereto, said projecting arm being provided with an extending tongue having two contiguous portions of different widths and a transverse end portion wider than either of said contiguous portions, a latch lever pivotally mounted upon said support and extending in substantially parallel spaced relation to said trip lever, said latch lever having a slot comprising two contiguous portions of different widths corresponding to said contiguous portions of said tongue and forming a camming shoulder therebetween, said projecting arm extending between said trip lever and said latch lever and said tongue being interlockingly engaged with said slot, said latch lever being also provided with an offset portion forming a camming shoulder positioned to be engaged by said end portion of said tongue positively to move said latch lever toward said trip lever, a tension spring interconnecting said latch lever and said trip lever on opposite sides of their pivot point to bias said latch lever to secure said trip lever in latching position and to bias said trip lever to disengage said detent, overcenter spring means responsive to the current passing through said switch contacts for moving said latch lever away from said trip lever in opposition to said spring thereby to disengage the wider portion of said tongue from said latching shoulder and permit said spring to actuate said trip lever to release said switch member, and means associated with said switch member for engaging said projecting arm to actuate said trip lever against the bias of said spring thereby to reengage said detent and to engage said camming shoulder for positively moving said latch lever to reset said overcenter spring means.

9. An adjustable snap-action thermo-responsive device comprising a support, an overcenter toggle lever mounted upon said support, a U-shaped actuating element having one leg formed of thermo-deformable material, said leg having its free end positioned to engage said toggle lever when deformed upon the application of heat thereto, resilient means for connecting the bight of said U-shaped actuating element to said support, and means for adjustably positioning the other leg of said actuating element with respect to said support thereby to control the setting of said thermo-responsive device.

10. An adjustable snap-action thermo-responsive device comprising an L-shaped support, an overcenter toggle lever pivotally mounted upon one leg of said support, a U-shaped actuating element including at least one leg formed of a strip of bimetallic material, said bimetallic leg being deformable upon the application of heat thereto to change the normal spacing between its free end and the other leg of said U-shaped actuating element and to engage and move said

overcenter lever, means for resiliently mounting said U-shaped actuating element at its bight upon the other leg of said support so that said actuating element extends in substantially parallel spaced relation with said first leg of said support, and means for adjustably positioning the free end of said other leg of said actuating element with respect to said support.

11. An adjustable snap-action thermo-responsive device comprising an L-shaped support, a bracket extending from a first leg of said support in a plane substantially perpendicular to both legs of said support, an overcenter toggle lever pivotally mounted upon said bracket, a U-shaped actuating element comprising an L-shaped mounting strip permanently connected to a strip of bimetallic material, a cantilever spring strip for resiliently attaching said U-shaped actuating element at its bight to the other leg of said L-shaped support in such a position that said mounting strip extends in substantially parallel spaced relation to said first leg of said support, said bimetallic strip being positioned to engage and actuate said overcenter lever when deformed by the application of heat thereto, and an adjusting bolt for varying the spacing between the free end of said mounting strip

and said first leg of said support thereby to change the setting of said thermo-responsive device.

12. A circuit breaker comprising a pair of co-operating switch contacts, a movable switch member for moving one of said contacts, a latch member normally engaging one end of said movable switch member, a pivoted arm for moving said latch member to disengage said switch member, a support providing means for pivotally supporting said arm, a U-shaped actuating element having a rigid leg and a leg formed of a strip of bimetallic material, said bimetallic leg having its free end positioned to engage said arm when deformed by the application of heat thereto, resilient means for connecting said U-shaped actuating element at its bight to said support, means for adjustably positioning said rigid leg of said actuating element with respect to said support, and an electric heating element positioned between the legs of said U-shaped actuating element and connected to carry a current proportional to the current traversing said contacts thereby to heat said bimetallic strip in accordance with the magnitude of said last named current.

WILLIAM LAWRENCE BUTLER.

CERTIFICATE OF CORRECTION.

Patent No. 2,318,987.

May 11, 1943.

WILLIAM LAWRENCE BUTLER.

It is hereby certified that error appears in the printed specification of the above numbered patent requiring correction as follows: Page 1, first column, lines 17-21 inclusive, strike out the following paragraph -

"My invention is especially useful in manually operated current responsive tripped circuit breaker which is trip-free in its automatic operation and which may be easily manufactured in large quantities and at low cost."

page 5, first column, line 40, for "position" read --portion--; and that the said Letters Patent should be read with this correction therein that the same may conform to the record of the case in the Patent Office.

Signed and sealed this 22nd day of June, A. D. 1943.

Henry Van Arsdale,

(Seal) Acting Commissioner of Patents.
